DESIGN FOR A SOAP DISPENSING STAND

Application filed March 12, 1931. Serial No. 39,061. Term of patent 14 years.

To all whom it may concern:

Be it known that we, RAYMOND L. RENZENHAUSEN and CHARLES F. POLLNOW, citizens of the United States, and residents of the city of St. Louis, State of Missouri, have jointly invented a certain new, original, and ornamental Design for a Soap Dispensing Stand, of which the following is a specification, reference being made to the accompanying drawings, forming a part thereof, in which—

Figure 1 is a perspective view,
Figure 2 is a side elevational view, and
Figure 3 is a plan view, of a soap dispensing stand embodying our new design.

We claim—

The ornamental design for a soap dispensing stand substantially as shown.

RAYMOND L. RENZENHAUSEN.
CHARLES F. POLLNOW.
